(57) **CLAIM**

The ornamental design for a vehicle front fender, as shown and described.

DESCRIPTION

FIG. 1 is an outer perspective side view of a driver side vehicle front fender showing our new design;

FIG. 2 is a side view thereof;

FIG. 3 is an inner side view thereof;

FIG. 4 is a perspective front view thereof; and,

FIG. 5 is inner perspective side view thereof.

It will be understood that the broken lines shown in the drawings illustrate portions of the vehicle front fender that form no part of claimed design.
